UNITED STATES PATENT OFFICE.

EDWARD L. GROSS, OF CHICAGO, ILLINOIS, ASSIGNOR OF ONE-HALF TO JOSEPH I. KOPPERL AND ONE-HALF TO CHARLES F. EIKER, OF CHICAGO, ILLINOIS.

SPRAYING APPARATUS OR THE LIKE.

1,086,819.

Specification of Letters Patent.

Patented Feb. 10, 1914.

Application filed October 23, 1912. Serial No. 727,329.

To all whom it may concern:

Be it known that I, EDWARD L. GROSS, a citizen of the United States, residing at Chicago, in the county of Cook and State of Illinois, have invented certain new and useful Improvements in Spraying Apparatus or the like, of which the following is a description.

My invention belongs to that general class 10 of devices known as spraying apparatus or the like for spraying or dispensing disinfectants, deodorizers, perfumes, or the like.

The device is particularly designed for use in dispensing disinfectants or deodorizers 15 in basements, bath rooms, toilet rooms, and in all places wherein it may be found applicable.

The invention has among its objects the production of a device of the kind described 20 that is simple, convenient, efficient, and satisfactory, that may be economically manufactured; that will not easily get out of order, and that may be used without expense of 25 maintenance other than the expense of replenishing the same with the disinfectant, deodorizer, or the like.

To this end my invention consists in the novel construction, arrangement and combination of parts herein shown and described, 30 and more particularly pointed out in the claims.

In the drawings, wherein like reference characters indicate like or corresponding parts, Figure 1 is a side elevation and partial sectional view of the preferred form of 35 my device, and Fig. 2 is an enlarged sectional view of the pumping and spraying mechanism.

Referring to the drawings, 1 represents a 40 tank or receptacle of suitable material, size and shape, which may be provided with brackets 2, 2 for securing the same in position, for example, to a wall. The same may also be provided with a suitable charging 45 inlet, around which may be arranged a funnel 3, or the equivalent, for convenience in filling. The disinfectant is discharged from a pipe 4, provided with a suitable nozzle, or the equivalent, as hereafter described.

Arranged within the receptacle is a pipe 5, 50 or tube 5, which is carried by a pipe 6, forming substantially a pump cylinder or casing, which is secured to the cap 7 at the top of the receptacle. The pipe 5 is provided with a check valve, which, in the device shown, is

a ball 8, the movement of the same being limited by the perforated plate 9. Adjustably arranged within the pipe 6 is a pipe 10, which is connected with the pipe 4. The pipe 10 serves as a pump rod, and is provided with a piston or plunger at its lower end. While any style of piston or plunger may be used, a very simple construction is shown in Fig. 2, in which 12 are cups of leather, or equivalent material, secured to the plunger rod 10 by nuts, or collars 14. As the pipe 10 is depressed, assuming the same to be in the position shown in Fig. 1, any fluid in the outer pipe or casing 6 is forced up through the pipes 10 and 4, and 70 discharged through the nozzle 21, the valve member 8 preventing its return to the receptacle. The movement of the rod or pipe 10 may be limited by the shoulder 11.

To operate the pump, I provide a bracket 75 15, which, in the construction shown, also secures the pipes 10 and 4 together. Secured to the bracket 15 is a rod 16, which extends through and is guided by the brackets 2. The lower end of the rod is 80 provided with a knob or ball 17, connected to the rod, either directly or through a chain 18, or other flexible connection. Arranged between the brackets is a spring 19, which bears against the lower bracket and against 85 a collar 20, upon the rod or bar 16. Pulling down on the rod 16 by means of the ball 17, lowers the pump piston substantially as shown in Fig. 2, forcing the fluid up through the pipe 10, and as soon as the ball 17 is released, the spring 19 causes the plunger to 90 rise substantially, as shown in Fig. 1.

The nozzle consists of a casing 21, having a discharge outlet 22. Within the nozzle is arranged a small rotatable member 95 23, having spiral grooves 24 upon the outside. The member 23 is also provided with a stem 25, which loosely slides in the interior of the pipe 4 and guides the member 23. As the fluid is forced out through the nozzle 100 the same rotates the member 23, which breaks the fluid up into a very fine vapor or spray.

The operation of the device may be briefly described as follows: Assuming that the 105 parts are in the normal positions shown in Fig. 1, and the desired kind and quantity of fluid in the receptacle 1. If the device has been previously operated, the chamber in the pipe 6 is filled with the fluid. If the 110

ball 17 is pulled down, the pump plunger is pulled down in the position as shown in Fig. 2, causing the fluid to flow out through the nozzle, the same being prevented from flowing back through the pipe 5 by the ball 8. As soon as the ball or handle 17 is released the spring pushes the plunger back to the position shown in Fig. 1. At this time the member 23 seats at the end of pipe 10 4, so that as the pipe 10 and the plunger or piston is raised, a fresh supply of fluid is drawn up from the receptacle up through the pipe 5 into the pipe 6.

It will be seen that the device is very simple, both in construction and in operation, and that it may be operated without any expense whatever except the expense of replenishing the fluid in the tank or receptacle. The device may be constructed of any material suitable for the use to which the device is to be placed, and may be finished or ornamented as preferred.

Having thus described my invention, it is obvious that various immaterial modifications may be made in the same without departing from the spirit of my invention, hence I do not wish to be understood as limiting myself to the exact form, construction, arrangement or combination of parts herein shown and described, or uses mentioned.

What I claim as new and desire to secure by Letters Patent is:—

1. In a device of the kind described, the combination of a suitable receptacle, pumping mechanism therefor comprising a pump casing having an intake pipe extending to proximate the bottom of the receptacle, a valve arranged in said intake pipe, a plunger arranged in said cylinder, a plunger rod having an opening therethrough, and means for operating said plunger rod including an actuating rod extending longitudinally of the receptacle along one side thereof and mounted on the receptacle for reciprocation, a connection between the upper end of the

said actuating rod and the plunger rod, and an operating handle portion at the lower end of the actuating rod.

2. In a device of the kind described, the combination of a suitable receptacle, pumping mechanism therefor comprising a pump casing having an intake pipe extending to proximate the bottom of the receptacle, a valve arranged in said intake pipe, a plunger arranged in said cylinder, a plunger rod having an opening therethrough, means for operating said plunger rod including a rod extending longitudinally of the receptacle along one side thereof and mounted on the receptacle for reciprocation, a connection between the upper end of the rod and the plunger rod, a spring operatively connected with said actuating rod and acting to force the same in one direction, and an operating handle portion connected with the rod and extending below the bottom of the receptacle.

3. In a device of the kind described, the combination of a suitable receptacle provided with laterally projecting portions at one side thereof near its top and bottom respectively, an actuating rod extending longitudinally of the receptacle and mounted in said portions for reciprocation, a coiled spring secured at one end to the said rod and having its other end in engagement with one of said projecting portions, said spring acting to force the actuating rod in one direction, a connection between the upper end of said rod and the plunger rod, and an operating handle portion at the lower end of said actuating rod.

In testimony whereof, I have hereunto signed my name in the presence of two subscribing witnesses.

EDWARD L. GROSS.
